UNITED STATES PATENT OFFICE

2,526,100

HAND SLED

Burnell E. Weirick, Kalamazoo, Mich., assignor to
 Kalamazoo Sled Company, Kalamazoo, Mich.,
 a corporation of Michigan

Application May 29, 1946, Serial No. 673,099

1 Claim. (Cl. 280—27)

1

The main objects of this invention are:

First, to provide a hand sled having knees which may be formed of relatively light sheet metal stock and at the same time are very rigid and capable of withstanding severe shocks and strains.

Second, to provide in a hand sled an improved knee structure which is graceful and attractive in appearance and at the same time strong and rigid.

Objects relating to details and economies of the invention will appear from the description to follow. The invention is defined in the claim.

A structure which embodies the features of the invention is clearly illustrated in the accompanying drawing, in which:

Fig. 1 is a side elevation of a hand sled embodying my invention.

Fig. 2 is an enlarged fragmentary view in transverse section on line 2—2 of Fig. 1.

Fig. 3 is a fragmentary plan view of one of the knees and a runner, the knee being partially in section on line 3—3 of Fig. 2.

Fig. 4 is a perspective view of the parts constituting a knee before the assembly of the parts.

The embodiment of the invention illustrated is a coasting sled of the steerable runner type, that is, the sled is steered by the flexing of the front ends of the runners. A sled of this type is illustrated in the patent to Kidder No. 2,243,345, issued May 27, 1941, but as these flexible runner steering features are known in the art and constitute no part of the present invention, they are not illustrated in detail herein.

In the embodiment of my invention illustrated the raves 1 of the top board 2 are secured upon the cross bars or benches 3. The runners 4 are of T cross section, the upwardly projecting web 5 providing means for attachment of the legs of the knees thereto. The knees, designated generally by the numeral 6, comprise the top or attaching brackets 7 having the downwardly diverging legs 8 formed integrally therewith as sheet metal stampings. The top or bracket portions 7 have bosses 9 and 10, the bosses 9 being provided with holes 11 adapted to receive the bolts 12 shown by dotted lines in Fig. 2, while the bosses 10 have slots 13 adapted to receive the bolts 14 shown by dotted lines in Fig. 2. This permits the legs to pivot on the bolts 12 and to oscillate on the bolts 14 which facilitates the steering or the flexing of the runners.

The legs 8 are of channel section, increasing in depth from the bracket downwardly. They are bifurcated at 15 to receive the web 5 of the runners and the bifurcations provide ears 16 receiving the rivet 161, see Figs. 2 and 3. The legs are provided with outer flanges 17 and with inner flanges 18, the inner flanges being of increasing width from bottom to top and having out-turned reinforcing edge portions 19. In the embodiment illustrated the outer edges 20 of the flanges 17

are outwardly curved. The legs and their flanges merge into the top brackets 7.

To further stiffen and reinforce the legs I provide the generally triangular reinforcing plates 21 which are curved to correspond to the curved edges 20 of the flanges 17 and have inwardly projecting flanges 22 on their vertical edges which are disposed in overlapping closely embracing relation to the flanges 17 and welded thereto as indicated at 23. The lower corners of the plates 21 extend to a point adjacent to the runner. The bracket portion 7 is provided with a projecting outer end portion 24 which overhangs the upper edge 25 of the reinforcing plate. The reinforcing plates are adapted to receive some emblem or indicia 26, the letter "K" being shown in the drawing.

This arrangement of parts permits the use of relatively light stock in the forming of the knees which is of advantage both from the standpoint of forming and in the cost of material, and also the general weight of the sled.

I have illustrated and described the invention in a highly practical embodiment thereof. I have not attempted to illustrate various modifications and adaptations contemplated as it is believed this disclosure will enable the embodiment of the invention as may be desired.

Having thus described my invention what I claim as new and desire to secure by Letters Patent is:

A knee for a hand sled comprising a top attaching portion and downwardly diverging legs integral therewith and of downwardly facing channel section of increasing depth from top to bottom thereof and bifurcated for attachment to a runner, the legs having outwardly projecting flanges along their outer edges, said flanges diverging downwardly along their length with said legs and converging slightly outwardly and downwardly laterally along their width, the edges of the flanges being laterally outwardly curved, and a triangular reinforcing plate conforming to said leg flanges and having inturned edge flanges closely embracing and welded thereto, the outer end of said top portion being in overhanging relation to the upper edge of said reinforcing plate which is disposed with its upper end closely adjacent thereto.

BURNELL E. WEIRICK.
